METHOD AND APPARATUS FOR LOCATING
WELL FLUID LOSS

Marshall B. Standing, Harry S. Yapple, and Malcolm Macaulay, Whittier, Calif., assignors to California Research Corporation, San Francisco, Calif., a corporation of Delaware

Application July 18, 1949, Serial No. 105,354

8 Claims. (Cl. 175—182)

1

This invention relates to a method and apparatus for investigating liquid flow conditions in deep wells, such as oil wells, and particularly refers to the location of a formation intersected by the well bore through which liquid from the bore is leaving the well.

The rotary method of drilling wells utilizes a circulating liquid, commonly designated "mud fluid," made from water, a gel material to impart viscosity and thixotropy, and a finely-divided substance of high specific gravity to give added density. When a large quantity of fluid is lost from the well bore into the formation so as to reduce materially the returns to the surface, the condition is generally designated "lost circulation." This may occur either at the bottom of the hole, for example, when the drill bit first penetrates a very porous stratum, or may occur at points along the well bore due to failure of the mud to form an adequate seal against porous formations. The location of this point of lost circulation by presently available procedures so that remedial steps may be taken, for example, cementing or the like, is time-consuming and costly.

It is an object of this invention to provide an improved method and apparatus for investigating the flow of liquid, usually drilling mud, in a well from which the drill pipe and bit have been removed, and from which liquid is being lost to a formation penetrated by the well bore.

Another object is to provide a method and apparatus which will give a positive indication at the top of the well of the interval at which mud fluid is being lost from the bore, by introducing a restricted quantity of a liquid which may be designated an electrolyte, having a different electrical resistivity from the liquid in the well bore, and observing whether or not it travels downwardly from the point of introduction.

Another object is to provide an apparatus for controllably introducing into the liquid already present in the well a separate restricted quantity of electrolyte having dissimilar electrical characteristics and at the same time continuously measuring the electric resistivity of the well fluid at points both above and below that at which the electrolyte is introduced.

These and other objects and advantages of this invention will be further apparent from the following description of an example and from the attached drawings describing and illustrating the method and apparatus as applied to locating a zone of lost circulation in a well.

In the drawings, Figure 1 is a diagrammatic

2

longitudinal sectional view of a well in which is placed an example of apparatus for carrying out this procedure. Figure 2 is a longitudinal sectional view of the upper portion of the liquid-releasing and resistance measuring apparatus shown in Figure 1. Figure 3 is a longitudinal sectional view of the lower or electrolyte storage portion of the apparatus shown in Figures 1 and 2.

Figure 4 is a connection diagram illustrating a form of valve control and particularly the power supply signal-generating and signal-transmitting equipment, which comprises the electrical components of this example.

Referring to the drawings and particularly to Figure 1, reference numeral 10 designates a conventional well bore, the upper end of which is cased at 11 and the lower end of which extends downwardly through subsurface formations designated 12, 13 and 14. The drilling and hoisting equipment therefor is not illustrated, but the well is designated as standing full of drilling fluid 15, which may be a slurry of clay, water, weight material, and, in some cases, viscosity-modifying chemicals such as phosphates, tannins and the like. Various non-aqueous or oil-base drilling fluids may also be employed. As stated above, one purpose of this drilling fluid is to form a thin, impervious sheath or cake 16 along that part of bore 10 below casing 11.

In this example, that part of sheath 16 opposite a highly pervious or even fractured or cavernous formation 13 is insufficient to prevent water or drilling mud from flowing outwardly into formation 13 under the hydrostatic head existing on drilling fluid 15 in the well and from that portion of the body of drilling fluid which is above the point or interval of "lost circulation." In order to identify which formation is receiving the fluid, the locator device generally designated 17 is lowered into the well on a multi-conductor insulated cable after the drill stem and bit are removed, and is sequentially positioned opposite various strata to determine where the slow downward flow of the drilling fluid ceases, due to outward leakage into the formation. At all points below this interval, the drilling fluid will be static, and this condition will be positively indicated by the method and means to be described.

The upper end of multi-conductor cable 18 passes over a pulley or hoisting mechanism 19 and leads through a recording device generally designated 20 to a control panel 21 in which certain of the circuits to be described below are contained for controlling the operation of the locator 17, and for indicating the electrical conditions in

the body of drilling fluid 15, to which it is adapted to respond.

Referring to Figures 2 and 3, the locator 17 there shown consists of a generally cylindrical member 22, to the upper and lower ends of which are threaded metal tubes 23 and 24, respectively, to form a housing. Each of these last-named tubes is covered substantially throughout its length with an electrically insulating coating 25 and 26, respectively, for example, rubber or "Neoprene," suitably bonded to the tubes. Desirably, but not necessarily, the inner surfaces may also be so coated. The upper end of tube 23 may be threaded as at 27 and provided with an upper cap 28 to secure a closure or head 29 to tube 23. Electrical connecting means of any desired type generally designated 30 to receive the lower end of multi-conductor cable 18 are secured to head 29 by a second cap and sealing means 31. The bottom of lower tube 24 is desirably closed by an end member 32.

Within the lower tube 24 and extending downwardly from member 22 is a cylindrical liner 33 through which a sealed piston 34 is adapted to move under the force exerted by a helical spring 35, the latter centered on a stud 36 on the upper face of member 32. A liquid passage 37 leads upwardly from the space above piston 34 in liner 33 to a T 38 threadedly connected to the top of member 22. The side outlet 39 of T 38 is provided with a check valve 40, the inlet of which is accessible from outside of upper tube 23 through port 41 in that tube. By the arrangement just described, it is possible to introduce through the inlet of check valve 40, T 38, and liquid passage 37 a quantity of liquid electrolyte 42 into the space above piston 34 in liner 33 against the force exerted by spring 35.

The upper end of T 38 is connected to an enclosed solenoid-actuated valve generally designated 43, the outlet of which leads through tube 44 to a liquid passage 45 in member 22. A plurality of radial passages 46 leads from passage 45 to circumferentially spaced distributors 47 mounted in an annular recess 48 surrounding member 22. By this arrangement, when solenoid valve 43 is actuated, the liquid 42, which is maintained under pressure by the piston and spring arrangement just described, is discharged slowly through distributors 47 into the space surrounding the locator 17 at substantially the midpoint of the latter. Ports 110 and 111 in tubes 23 and 24 permit well fluids to enter the housing and maintain hydrostatic equilibrium inside and outside the latter.

Liquid electrolyte 42 is chosen to have a substantially lower electrical resistivity than that of the aqueous or non-aqueous drilling fluid 15 present in the well bore 10, but is desirably of substantially the same density and viscosity and of such a chemical nature that it will not flocculate or otherwise modify the properties of the drilling fluid 15 into which it is introduced as just described. For example, if the drilling fluid has a specific resistivity of from 100 to 400 ohm-cms., the resistivity of the liquid 42 is desirably adjusted to be from 20 to 50 ohm-cms. A specific example of a formulation is given below which proved quite successful in locating a zone of lost circulation in a well at Montebello, California, using a clay-water mud to which large quantities of swelling bentonite had previously been added in an attempt to plug the porous formation. After locating the lost circulation zone, it was cemented and circulation was estab-

lished without difficulty. The electrolyte in that case consisted of the following materials in the proportions given:

	Parts by weight
5 Tetrasodium pyrophosphate (to prevent flocculating the drilling fluid)	3
15 Salt-sodium chloride	5
Sugar (to give a density comparable to the drilling fluid)	50
10 Fresh water	100

This electrolyte had an electrical resistivity of approximately 30 ohm-cms.

It will be appreciated from the foregoing that if locator 17 is positioned at a predetermined point in the well and the drilling fluid 15 is being lost through a lower formation, the electrolyte 42, which is ejected in a restricted amount and during a short period, will form a substantially annular sheath around locator 17 and will be carried downwardly along its outer surface by the motion of drilling fluid 15. If the locator 17 is below the point at which the circulation is being lost, the slug of electrolyte will remain substantially at the point of ejection from the distributors 47, due to its comparable density and viscosity.

In order to determine electrically the direction of travel of this liquid sheath, upper electrodes 49 and 50 and lower electrodes 51 and 52 are positioned in electrical contact with a short length of the well liquid and around the insulating coverings 25 and 26, respectively, of locator 17, the electrodes being desirably equidistant from distributors 47. Separate insulated leads generally designated 53 are provided from each of the electrodes and are connected to corresponding insulating bushings generally designated 54 in the cap 55 of a fluid tight housing 56 positioned in the upper tube 23 of locator 17. In addition to providing electrical connections for electrodes 49 to 52, inclusive, a pair of such insulating bushings are also provided for the electrical connections 57 of solenoid valve 43 described above.

Figure 4 illustrates a connection diagram and a desirable example of control and signal transmitting circuits, most of which may be contained within housing 56, with suitable connections to cable 18 which will transmit the control impulses and the resulting signals to recorder 20 at the top of the well. Letters A, B, C, D, E and F represent the several conductors in multi-conductor cable 18, with the portions above the broken lines in each of the conductors indicating that part of the circuit connected to the recorder 20 and the control panel 21 at the top of the well through cable 18. The remainder of the equipment connected to conductors A, B, C and D, as well as that connected to electrodes 49, 50, 51 and 52 is adapted to be inserted in housing 56 of locator 17.

As indicated in the drawing, a source of DC potential is applied as an operating source for the equipment through conductor C which in turn is connected to line 58. While not shown in the present arrangement, it will be apparent that through a suitable resistance, the heater voltages for the various tubes may be provided from line 58. Since it is desirable to use only AC across the electrodes 49 and 50 or 51 and 52 to avoid the polarization effects that would result if direct current were used between the electrodes, an alternating current generator, such as an oscillator, indicated generally as 59, is pro-

vided by tube 60 which is of the pentode type and a phase inverting network provided by resistors 61, 62 and 63 and condensers 64, 65 and 66. By the proper proportioning of the condensers 64, 65 and 66 and the resistors 61, 62 and 63, tube 60 may be caused to oscillate in a manner well known in the art since the plate 67 and grid 68 of tube 60 will be substantially 180° out of phase. In order to provide the desired operating potential to the screen grid 112 and plate 67 of the tube, resistors 69 and 70 are respectively provided for connecting the screen grid and the plate to the source of DC potential. As shown, grid biasing is provided by cathode resistor 71 and a by-pass condenser 72 is provided between cathode 73 and the circuit ground which is isolated from the housing of locator 11 and returned to the surface by conductor D to avoid polarization effects. In order to amplify the output of the alternating current signal from tube 60, the output of plate 67 is coupled to the grid 74 of tube 75 through the coupling condenser 66. Tube 75 is likewise of the pentode type and is provided with grid biasing by cathode resistor 76 connected between cathode 77 and ground. Plate 78 of tube 75 is connected to the primary winding 79 of a power output transformer 80.

Secondary winding 81 of the output transformer 80 is connected across the terminals of a Wheatstone bridge circuit comprising impedance elements, such as resistors 82 and 83 and the impedance of the well fluid measured between electrodes 49 and 50 and 51 and 52. The interconnection from secondary 81 of transformer 80 is provided by line 84 which is connected to a common point between resistors 82 and 83. Likewise, line 85 is connected between the other side of secondary 81, and both of the top electrodes 49 and 51 of the upper and lower pairs of electrodes respectively on the locator 11. Since the output of the opposite pair of terminals of the Wheatstone bridge circuit formed by the electrodes and resistors 82 and 83 may be relatively small, the output is connected to suitable amplifying means through the primary winding 86 of transformer 87. Secondary winding 88 of transformer 87 is in turn connected through two stages of amplification provided by tubes 89 and 90 to the primary 91 of output transformer 92. In order to provide the desired amplification with a phase shift of 180° between the secondary winding 88 of transformer 87 and the primary 91 of transformer 92, primary winding 91 is connected between the cathode 93 of the tube 90 and ground instead of through the usual plate grid coupling as between tubes 89 and 90. The resistor and condenser coupling between tubes 89 and 90 are proportioned to obtain a zero phase shift of the signal between the tubes and thereby maintain the desired 180° phase shift produced by tube 89. The purpose of this 180° phase shift through the amplifier will be explained more fully hereinafter in the description of the operation of the circuit.

In order to provide a reference AC voltage to the output of the circuit, transformer 94 is connected with its primary winding 95 parallel with secondary winding 81 of transformer 80. Secondary windings 96 and 97 of transformers 94 and 92, respectively, are connected to synchronous rectifier means indicated generally as 98. Synchronous rectifier means 98 preferably comprises a pair of rectifiers 99 and 100, a volt-

age-dividing potentiometer 101 and an impedance element, such as resistance 102 having an impedance approximately equal to the impedance of secondary winding 97, to which are connected the operating voltages obtained from secondaries 96 and 97 of the two transformers 94 and 92, respectively. For balancing potentiometer 101 when there is no input signal from the amplifying means, an adjustable center terminal 103 is connected to one side of secondary 96, opposite the common connection of resistance 102 with secondaries 96 and 97.

As shown in the drawing, indicating means such as a DC zero center meter 104 is provided across the terminals of rectifiers 99 and 100 and the potentiometer 101. It will be apparent that meter 104 is only representative of the recorder indicated generally in Figure 1 as recorder 28.

Operation of the circuit is as follows: Before electrolyte 42 is introduced into the well by momentary actuation of the solenoid 43 through operation of the switches in lines E and F, the resistance between electrodes 49 and 50 is approximately equal to the resistance between electrodes 51 and 52, and since the resistors 82 and 83 are selected to balance the bridge circuit provided by these resistors and the resistance of the well fluid across the electrodes, there will be a zero voltage generated across primary 86 of transformer 87, and accordingly there will be no voltage across the secondary winding 97 of transformer 92. Thus, the only current flowing through synchronous rectifier 98 is that produced by the current flow through transformer 94. Due to the reference potential obtained from transformer 80 and by properly positioning center terminal 103 on potentiometer 101, it will be apparent that the current flow through the left-hand portion of potentiometer 101 and the right-hand portion of the potentiometer will be equal on opposite half-cycles of the alternating current and the current through meter 104 may be arranged to read zero under these conditions. However, when the slug of resistance modifying liquid has been introduced into the well and permitted to flow in accordance with the direction of flow of the circulating fluid, it will be apparent that a change in the impedance, or resistance, between one pair of electrodes, say 51 and 52, may be reduced sufficiently below the impedance, or resistance, between electrodes 49 and 50 to cause a greater amount of current to flow in the lower arm of the bridge. Under these conditions the primary 86 of transformer 87 will be energized with an alternating current potential either in phase with that of secondary 81 of transformer 80 or 180° out of phase with secondary 81. The direction of polarization of transformer 87 will be dependent, of course, upon the resistance characteristics of the fluid introduced into the well bore and the resultant output will be determined by the same properties. The output signal from the electrodes, of course, appears across the secondary 97 of transformer 92, and it will be noted that secondaries 96 and 97 of transformers 92 and 94 are connected in series across rectifier 99 and the left-hand portion of potentiometer 101 through the center terminal connection 103. In this way it is possible for the signal derived from the electrodes to be either in phase with the reference voltage from secondary 96 or 180° out of phase with this voltage, thereby causing the signal across the left-hand portion of potentiometer 101 to be either in-

creased by the additive action of the signal voltage from transformer 92 or decreased, depending upon the direction of flow of the fluid between the electrodes. If, for example, it is assumed that the direction of the instantaneous A. C. pulses through the transformers are as shown in the drawing, it will be apparent that the potential across the left-hand portion of 101 will be decreased and hence the D. C. potential across meter 104 will be such that current flows from B to A through the meter. On the other hand, if the potential appearing at secondary winding 97 of transformer 92 is in phase with that flowing through winding 96, the current across the left-hand section of potentiometer 101 will be increased and the voltage across the right-hand portion of the potentiometer will be greater than with zero signal applied to the transformer 92. Hence, the flow will be from terminal A to terminal B and the direction of deflection of meter 104 will be reversed. It will therefore be apparent that the deflection of the meter will be an indication of the direction of flow of the fluid.

If an indication of the rate of flow of the electrolyte is desired, the time interval between the operation of solenoid-actuated valve 43 and the deflection of meter 104 may be measured and divided by the distance between distributors 47 and the electrodes.

While further modifications and changes will be apparent to those skilled in the art, all such modifications and changes that fall within the scope of the appended claims are embraced thereby.

We claim:

1. An apparatus for determining that location in a well at which fluid is being lost to a formation including an elongated housing having a non-conducting outer surface for at least a portion of its length and adapted to be lowered into a well by a multi-conductor insulated cable, means forming a liquid reservoir in said housing, liquid pressurizing means for said reservoir, a liquid outlet intermediate the ends of said housing, a passage from said reservoir to said outlet, an electrically actuated valve in said passage, said valve adapted to be actuated through said cable to release a charge of liquid from said outlet, two pairs of insulated electrodes on said housing spaced on each side of said liquid outlet, and electrical means in said housing connected to said electrodes and said cable for converting changes in electrical resistance between either of said electrode pairs due to presence of said liquid charge therebetween into a direct current signal which is transmitted through said cable to the top of said well, and an indicator connected to the upper end of said cable.

2. An apparatus according to claim 1 in which said liquid outlet comprises a plurality of circumferentially spaced nozzles to produce a substantially annular charge of liquid adjacent said housing.

3. Apparatus for determining the location in a drill hole at which fluid is being lost to a formation comprising an elongated housing having at least a portion of its surface insulated and adapted to be lowered into said hole by a multi-conductor insulated cable, electrolyte storage means within said housing, pressurizing means for expelling electrolyte from said storage means, relay means actuatable from the surface to permit said pressurizing means to expel electrolyte from said storage means to said hole, two pairs of

electrodes adapted to be bridged by said electrolyte equally spaced above and below the point at which said electrolyte is expelled, and electrical means for indicating the direction of flow of said electrolyte, said electrical means comprising a source of direct current, and A. C. signal generator energized by said source, means for connecting said source, means for connecting said generator across the terminals of a bridge circuit including a pair of impedance elements and said pairs of electrodes, amplifying means connected between the opposite terminals of said bridge circuit, synchronous rectifier means having the output of said amplifying means and said generator so connected thereto that the phase of the signals from said amplifying means and said generator may be compared, and indicating means connected to said synchronous rectifier means to detect the phase of said amplifying means and thereby identify the pair of electrodes between which said electrolyte is present.

4. Apparatus for determining the location in a drill hole at which fluid is being lost to a formation comprising an elongated housing having a portion of its surface insulated and adapted to be lowered into said hole by a multi-conductor insulated cable, electrolyte storage means within said housing, pressurizing means for expelling electrolyte from said means, relay means actuatable from the surface to permit said pressurizing means to expel electrolyte from said storage means into said hole, two pairs of electrodes equally spaced above and below the point at which electrolyte is expelled and adapted to be bridged by said electrolyte, and electrical means for indicating the direction of flow of said electrolyte, said electrical means comprising an A. C. signal source, means for connecting said generator across a bridge circuit including said electrode pairs and a pair of resistances similar to the resistance of said electrode pairs when bridged by the fluid being lost, amplifying means for the output of said bridge, synchronous rectifier means comprising a potentiometer, a pair of rectifier elements connected to the ends of said potentiometer, and a pair of impedance elements connected in series with the opposite terminals of said rectifiers, one of said elements being an output load for said amplifying means, said A. C. signal source being connected between the midpoint of said potentiometer and the junction of said impedance elements to provide a phase comparison for the output signal from said amplifying means, and indicating means connected across said potentiometer to indicate the phase of the voltage from said bridge circuit and thereby identify the pair of electrodes bridged by said electrolyte.

5. An apparatus for determining the direction of flow of fluid in a well bore comprising an elongated housing having an electrolyte reservoir therein, means for suspending said housing in said bore, and means for introducing electrolyte to said bore from said reservoir, an electrical circuit for determining the direction of movement of said electrolyte comprising a source of alternating current, a Wheatstone bridge connected to said source, an arm of said bridge being provided by a pair of longitudinally spaced electrodes mounted upon said housing below said electrolyte introducing means, said electrodes being insulated from said housing, and means for detecting a change of impedance in said arm due to said electrolyte flowing downwardly to bridge said electrodes, said last-named means including

amplifying means, a synchronous rectifier connected to said amplifying means and said source of alternating current so that the unbalanced voltage from said bridge will be in phase or 180° out of phase with said source and potential indicating means connected to said rectifier to indicate an unbalanced condition in said arm.

6. In a method of testing a well from which there is a movement of liquids out of said well into a formation through which said well passes, the steps of introducing into the liquid in said well at a predetermined level a restricted charge of an electrolyte fluid having a viscosity and density substantially the same as the liquid already in said well to vertically displace a volume of said liquid with said electrolyte fluid, said electrolyte fluid having an electrical resistivity differing from that of said liquid, continuously measuring the electrical impedance of a volume of liquid at a level below said predetermined level and recording the measurement of said impedance to indicate the displacement of said well liquid by said electrolyte fluid and thereby detect movement of said well fluid with respect to said predetermined level.

5

10

7. A method according to claim 6 in which said introduced charge of fluid has an electrical resistivity of less than about 25% of that of the well liquid.

8. A method according to claim 6 in which said introduced charge of fluid has an electrical resistivity differing from that of the well liquid by a factor of not less than four.
